CLAIM

We claim the ornamental design for a digital camera, as shown and described.

DESCRIPTION

FIG. 1 is a front, right side perspective view of our new design for a digital camera with an LCD display rotated inward and closed against the camera body;

FIG. 2 is a rear, right side perspective view of the design shown in FIG. 1;

FIG. 3 is a front, top, right side perspective view of the design shown in FIG. 1 with the LCD display rotated outward away from the camera body;

FIG. 4 is a front elevation view of our new design for a digital camera with the LCD display rotated inward and closed against the camera body;

FIG. 5 is a top plan view of the camera in the configuration of FIG. 1;

FIG. 6 is a rear elevation view of the camera in the configuration of FIG. 1;

FIG. 7 is a bottom plan view of the camera in the configuration of FIG. 1;

FIG. 8 is a left side elevation view of the camera in the configuration of FIG. 1; and,

FIG. 9 is a right side elevation view of the camera in the configuration of FIG. 1.

UNITED STATES PATENT AND TRADEMARK OFFICE
CERTIFICATE OF CORRECTION

PATENT NO. : Des. 528,141 S
APPLICATION NO. : 29/225934
DATED : September 12, 2006
INVENTOR(S) : Hiroyuki Kinemura et al.

Page 1 of 1

It is certified that error appears in the above-identified patent and that said Letters Patent is hereby corrected as shown below:

In the Inventor's place of residence:

Please delete "Hiroyuki Kinemura, Hyougo (JP)" and "Motohiro Sasada, Hyougo (JP)"
and substitute with -- Hiroyuki Kinemura, Hyogo (JP) and Motohiro Sasada, Hyogo
(JP) --.

Signed and Sealed this

Nineteenth Day of December, 2006

A handwritten signature in black ink, appearing to read "Jon W. Dudas". The signature is written in a cursive style with a large, stylized "D" and "u".
